UNITED STATES PATENT OFFICE.

EDWARD G. PFAHL, OF ROCHESTER, NEW YORK.

APPARATUS FOR FEEDING AND DISTRIBUTING VINEGAR STOCK.

Application filed July 11, 1924. Serial No. 725,499.

The object of this invention is to provide an improved apparatus for feeding vinegar stock into the vinegar generator.

Another object of this invention is to make 5 the apparatus adjustable so that it is possible to distribute the vinegar stock over a large or small area.

These and other objects of this invention will be fully illustrated in the drawing, de- 10 scribed in the specification and pointed out in the claims at the end thereof.

In the accompanying drawing:

Figure 1 is a perspective view of the feeding and distributing mechanism mounted on 15 top of the vinegar generator, the parts being partly broken away to illustrate the construction of the mechanism.

Figure 2 is a vertical sectional view of the distributing or spraying cup and feed pipe 20 leading thereto.

In the figures of the drawing like reference numerals indicate like parts.

The subject matter of my present invention is an improvement on the apparatus ill- 25 lustrated in my prior patent issued to me September 18th, 1923, Patent No. 1,468,394. This improvement comprises means that make it possible to build the feeding and distributing mechanism as a unit, independ- 30 ent of the vinegar generator into which the vinegar stock is to be fed by it. As illustrated in the drawing the feeding apparatus consists of the container 1 that is supported in angular recesses provided in the cross bars 35 2 and 3, these recesses being shaped to tilt the container up at the back. In this container is suspended the tipple 4 by means of the shaft 5. The shaft 5 engages suitable pockets one on either side of the container 1 40 in which it can turn to swing the tipple to discharge its contents into the container. The tipple is formed in the form of a scoop having two sides, bottom and one end, the other end being omitted to allow the vinegar stock to be discharged from the tipple at 45 this point. The shaft 5 on which the tipple is supported to swing in the container passes thru the sides of the tipple and is suitably held in place thereon.

50 The top of the container is closed by the cover 6. In this cover is provided an opening 7 thru which the vinegar stock is fed from a suitable reservoir into the feeding mechanism. For this purpose a spigot is 55 provided on the end of the hose leading from the reservoir. The nozzle of this spigot

leads into the opening 7 in the cover to direct the stream of the vinegar stock direct into the tipple.

The tipple 4 is normally suspended by the 60 shaft 5 with its open front end tilted up so that the vinegar stock flowing out of the spigot will accumulate therein. As the tipple is being filled with vinegar stock this inclination of the tipple gradually increases until 65 the rear end of the bottom of the tipple rests on the block 9 placed in the bottom of the container to form a suitable support for the tipple at a predetermined inclined position thereof. Any additional liquid which is fed 70 into the tipple after it rests on the block 9 with its rear end begins to gradually fill the tipple to the point where the weight of the liquid contained in the forward portion of the tipple gradually counterbalances and then 75 overbalances the weight in the rearward portion of the tipple. The tipple will tip at the front end as soon as the weight of the liquid in the forward portion of the tipple overbalances the weight of the liquid in the 80 rear portion of the tipple. When this happens all of the liquid which has accumulated in the tipple is dumped quickly into the container 1 in which the tipple is mounted to swing. The forward tilting of the tipple 85 after it has been overbalanced as above pointed out, is arrested by a pair of blocks 10 and 11 mounted in the bottom of the container 1. Under the forward end of the bottom of the tipple a pair of similar blocks 12 and 13 are 90 fastened, with which the blocks 10 and 11 make contact to arrest the front end of the tipple at a suitable distance from the bottom of the container 1.

After each dumping operation, that is, as 95 soon as the vinegar stock is drained from the tipple, it automatically returns to its normal inclined position, due to the fact that the tipple when empty is slightly overbalanced toward the rear end thereof, as heretofore pointed out, and when filled the tipple is overbalanced toward the front. A second hatch is then ready to be run into the tipple and finally dumped into the container 100 as above described. This cycle of operation repeats itself with unerring regularity as 105 long as the stream of liquid vinegar stock continues to flow into the tipple from the vinegar stock reservoir.

Threaded into the bottom of the container 110 1 near the front end thereof is the pipe 14 having the sprayer cup 15 supported on the

lower end thereof. This pipe projects downwardly into the vinegar generator and holds the spraying cup suspended at suitable distance above the filtering material contained in the generator. The spraying cup comprises a disc having an annular channel formed in the face thereof. The channel has a curved bottom and curved sides that converge in the center of the cup into a cone 16. The apex of the cone 16 projects above the spraying cup. A threaded hole passes thru the center of the spraying cup to receive the threaded stem 17 depending from the sleeve 18. The stem 17 is centered within the sleeve 18, being bent at an angle toward the inner wall of the sleeve 18 into which it passes to be suitably welded or riveted thereto. The spraying cup 15 is adapted to be threaded up or down on the stem 17 to increase or decrease the distance between the face of the cup and the lower end of the pipe 14. A locknut 19 is provided to lock the spraying cup at any desired elevation on the stem 17. The sleeve 18 is held in place in the lower end of the pipe 14 by means of a suitable setscrew 19 which clamps the sleeve in place within the tube.

The spraying cup is located centrally of the generator as it is held suspended from the container by the pipe 14. Both the pipe 14 and sprayer cup 15 are made of hard rubber or any other acid resisting material. The sleeve 18, threaded stem 17 and set screw 19 for holding the sleeve 18 in place within the lower end of the pipe 14 are preferably made up of Monel metal which is also acid resisting and will stand up under the action of vinegar stock.

When the vinegar stock is dumped into the container by means of the mechanism heretofore described the liquid will siphon out of the opening in the bottom of the pipe 14 without accumulating in the bottom of the container. The pipe 14 is large enough so that the liquid passing into it will quickly drain therefrom into the spraying cup 15.

The pressure with which the liquid drops onto the spraying cup, due to the height of the column of liquid in the pipe, forces the liquid down on the curved sides of the cone formed in the center of the cup and up the curved side of the channel formed therein, spreading the liquid over the surface of the filtering material by spraying it in a thin sheet concentrically to the spraying cup. The curvature of the outer wall of the channel on the spraying cup is designed to deflect the liquid upwardly at an angle which will throw the liquid over a predetermined area within the vinegar generator at the beginning of the spraying operation when the weight of the liquid column within the tube 14 is the greatest. As the liquid column diminishes in height, with a corresponding

reduction in the pressure at which it is forced out of the end of the pipe, the liquid is sprayed a gradually shorter distance in a way that will cover the whole of the surface of the filtering material within the range of the spray that is produced by the maximum pressure of the liquid column. This range of the spray can be varied by changing the location of the spraying cup on the end of the pipe 14. This is done by threading the cup up or down on the threaded stem so as to increase or decrease the space between the end of the pipe 14 and the face of the spraying cup 15. Thus when the face of the spraying cup is held close to the end of the pipe 14 the liquid passing out of the pipe into the cup is forced out over a larger area than is the case when the cup is lowered on the threaded stem and the distance increased between the end of the pipe 14 and the face of the spraying cup. In this way the spraying cup can be adjusted to spray the vinegar stock over a large or small area according to filtering area exposed within the vinegar generator.

The container with its dumping mechanism and spraying mechanism is thus made up in a single unit that can be moved and mounted as such in any desired position on top of any vinegar generator with the distributor within the generator.

From an inspection of Figure 2 it will be seen that the pipe 14 is enlarged at the lower end thereof to receive the sleeve 18. In this way the inner wall of the pipe 14 and the inner wall of the sleeve 18 form a continuation of each other permitting an unobstructed flow of the liquid therethrough.

I claim:

1. In an apparatus such as described, the combination of a base adapted to rest on the generator top, a measuring tank, a diffuser carried by the base beneath the latter and adapted to distribute the mix over the generator filling, and means carried by the base for delivering the mix from said tank to the diffuser, said base together with said diffuser and delivering means being removable from the generator as a unit.

2. In an apparatus such as described, the combination of a base adapted to rest on the generator, a measuring tank pivoted on the base, means for regulating the tilting of said tank, a diffuser carried by the base beneath the latter, and means carried by the base for delivering the mix from said tank to the diffuser, all of said elements together with said base being removable from the generator as a unit.

3. In an apparatus for feeding and distributing vinegar stock the combination of a base adapted to rest on the generator top, a measuring tank, a diffuser carried by the base beneath said container and adapted to distribute the mix over the generator filling,

and means carried by the base for delivering the mix from said tank to said diffuser, said base together with said diffuser and delivering means being removable from the generator as a unit.

4. In an apparatus for feeding and distributing vinegar stock the combination of a measuring tank, a sprayer carried beneath said measuring tank, means for delivering the vinegar stock to said sprayer, and means for adjusting said sprayer with relation to said delivering means to increase or decrease the spraying range of said sprayer.

5. In an apparatus for feeding and distributing vinegar stock into a generator, the combination of a measuring tank, a feed pipe depending from said measuring tank, a sprayer cup suspended from the end of

said feed pipe, said sprayer cup being adjustable toward or away from the end of said feed pipe to increase or decrease the distance between the face of said sprayer cup and the end of said feed pipe.

6. In an apparatus for feeding and distributing vinegar stock into a generator, the combination of a measuring tank, a feed pipe depending from said measuring tank, a sleeve within the end of said feed pipe, a stem suspended with said sleeve, a spraying cup suspended on said stem and being adapted to be adjusted up or down on said stem to increase or decrease the distance between the face of said sprayer cup and the end of said feed pipe.

In testimony whereof I affix my signature.
EDWARD G. PFAHL.
